UNITED STATES PATENT OFFICE

EDGAR G. PETERSEN, OF CHICAGO, ILLINOIS, ASSIGNOR TO PINES WINTERFRONT COMPANY, OF CHICAGO, ILLINOIS, A CORPORATION OF DELAWARE

RADIATOR SHUTTER

Application filed December 6, 1929, Serial No. 412,195, and in Germany June 18, 1928.

The present invention relates to radiator shutters, and is particularly concerned with built-in shutters for the radiators of internal combustion engines.

One of the objects of the present invention is the provision of a novel radiator core and shutter assembly, whereby the shutter unit is more securely and efficiently mounted upon the radiator core, so as to control all of the air passing through the core and direct air from the shutters through the most effective portions of the core.

Another object is the provision of a novel means of support for a built-in shutter upon a radiator core, in which the shutter is carried by relatively strong parts of the radiator core, so that there is no possibility of the injury of the honeycombed portion of the core, and no possibility of loosening or rattling of the shutter.

Another object of my invention is the provision of a novel shutter and radiator core assembly comprising a shutter frame supported directly upon integral flanges carried by the radiator core and eliminating the prior modes of support which are apt to damage the core structure.

Another object of the invention is the provision of a novel built-in shutter assembly capable of long periods of service without rattling, and which includes a plurality of false shutters for permanently closing the lower openings of the radiator core where the cooling fluid is liable to freeze at extremely low temperatures.

Other objects and advantages of the invention will appear more fully from the following description and from the accompanying drawings, in which similar characters of reference indicate similar parts throughout the several views.

The present application is directed particularly to the radiator core and shutter unit assembly, and is a continuation in part of my prior application, Serial No. 268,491, filed April 9, 1928, for radiator shutters.

Referring to the drawings, of which there are two sheets;

Fig. 1 is a front elevational view of my

built-in shutter assembly partially broken away to show the shutter structure;

Fig. 2 is a side elevational view of the radiator core in partial section;

Fig. 3 is a vertical section taken through the shutter unit on the plane of the line 3—3 of Fig. 1;

Fig. 4 is a vertical section taken through the entire assembly, on the plane of the line 4—4 of Fig. 1;

Fig. 5 is a fragmentary horizontal section, taken on the plane of the line 5—5 of Fig. 1.

Referring to Fig. 2, 23 indicates a radiator core having a pair of lateral frame members 24 and 25, preferably formed of sheet metal, and forming the sides of a core of the usual construction having honeycombed channels, tubes or other members adapted to permit the circulation of water, and to present an increased cooling area for the passage of air. The exact construction of the honeycombed portion 22 of the core is immaterial and does not affect the merits of the present invention, and any of the conventional forms of tubing or honeycombed construction may be employed.

The side frame members 24 and 25 of the core, preferably form the outer walls of the core, and are preferably provided with integral forwardly projecting flanges 26 and 27 for the support of a shutter frame and shutters further to be described. The side walls 24, 25 of core 23, are thus provided with forward continuations adapted to provide a support for a radiator shutter, and to aid in directing the air which passes through the shutters into the honeycombed portions 22 of the core.

While the flanges 26 and 27 are preferably integral parts of the radiator core wall or radiator band, it should also be understood that existing core structures may be adapted to support shutters according to the present invention, by the addition of flanges which are not necessarily integral parts of the band, and all embodiments of the invention do not necessarily include all of the preferred features.

The integral flanges 26 and 27 are preferably provided with elongated apertures 28

for the attachment of the shutter frame by a plurality of bolts 29, the elongated apertures permitting a slight adjustment of the shutters and frame relative to the core. The base of the radiator core 23 may be enclosed by a sheet metal wall 30 and the back of the core provided with the usual conduit 31 for water circulation.

The upper portion of the core includes a chamber having outside walls 36, 37 and 38, the rear wall 38 being provided with the usual conduit for connecting the upper portion of the radiator to a water jacket of an internal combustion engine. The upper wall 37 and front wall 36 are provided with an aperture 39, over which is welded a cast metal spout fitting 40 of any conventional form. The upper water box 36a, which is formed by the walls 36, 37, 38, is, of course, in communication with the honeycombed portion 22 of the core 23.

I shall now describe the radiator shutter unit 21, together with the operating mechanism which may be utilized either for thermostatic control, manual control or other controlling devices.

Referring to Fig. 3, I have here illustrated the improved shutter frame construction consisting of an end frame member 75 at the top, a pair of side frame members 76 and 77, and an end frame member 78 at the bottom. The end frame member 75 comprises a sheet metal strip, preferably of steel, having a downwardly extending flange 79 on its front side adapted to cover a bearing strip 80, further to be described.

The frame member 75 may also be formed with a depending flange 81 at its rear edge for stiffening the same, and is provided with a plurality of equally spaced apertures 82 for receiving the trunnions 83 of a plurality of shutters 84. At each end, the end frame member 75 may be provided with an attaching flange 85 bent down at substantially right angles and the downwardly extending flange 79 may be widened as at 86 to provide an auxiliary attaching flange on the front of the frame member.

The side frame members 76 and 77 may each be formed in a similar strip of sheet metal having a narrow flange 87 bent inward at substantially right angles on the rear edge to form a channel. At its forward edge, the frame member 76 is provided with a flange 89 bent inward at substantially right angles, and adapted to fill in the space between a rectangular fenestration for the shutters, and the inner edge of the shell 20.

The lower frame member 78 comprises a stamped sheet metal member, preferably of steel, having a plurality of false shutters 95 of the same size as the shutters 84 stamped therein, together with a substantially flat edge 96 for engagement with the inner edge 97 of the shell 20. The outer edge 98 of the

false shutter plate 94 conforms substantially to the inner boundary of the shell 20, projecting beneath said boundary and being engaged thereby. The frame member 78 may be formed with a pressed bead 98 at the upper end of false shutter 95, one side of the bead comprising the horizontal flange 92 having a plurality of apertures 99 to receive the trunnions of the shutters 84. At each end the horizontal flange 92 is turned up to form an attaching flange 101 adapted to be received in the channels 102 of the side frame members.

Centrally located in the false shutter plate 96 is an aperture 129 adapted to register with the engine shaft for the insertion of a crank, and this aperture may be closed by a cover plate 133 of any convenient or desirable form. The false shutter plate 94 is thus adapted to permanently close the lower end of the radiator core, and to provide a finished appearance simulating shutters which extend the full height of the front of the radiator. The lower part of the radiator core which contains the water most apt to be frozen, is thus shut off from circulation of the cooling air, thereby decreasing the possibility of freezing when the temperature unexpectedly drops below the freezing point of the cooling liquid.

The shutters 84 comprise strips of sheet metal, preferably outwardly curved as at 103, and having one edge 104 curved about a rod 105, which projects at both ends of the shutter and forms the trunnions 83. The opposite edge of the shutter is formed with a pressed curved groove 106 adapted to fit against the curved portion 104 of the adjacent shutter, to completely seal the intervening opening when the shutters are in closed position, and each of the shutters is preferably provided with an actuating arm comprising an inwardly turned flange 107 at the upper end of the shutter having an aperture.

The shutters may be secured together for simultaneous actuation by a shutter bar 109, provided with a plurality of rivets which are pivotally connected to the flanges 107 on the shutters. The actuating bar 109 bears a rivet 111 projecting upward through a slot in the upper frame member 75, and the rivet 111 may be pivotally connected to an actuating link 113.

The actuating bar 109 and link 113 are urged toward the left in Fig. 1 by a coil spring 74 secured to one end of the link 113 by being hooked about a rivet 114, and secured at its other end by being hooked about a rivet 115 carried by a frame member 75. Any form of manual or thermostatic operation may be utilized for actuating the shutters and the present construction is particularly adapted to maintain the adjustments made to insure operation at a predetermined temperature, on account of the firm and rigid securement of the shutter unit to the core unit.

The bearing strips for the more simple types of shutters may comprise integral parts of the shutter frames, such as the frame members 75, 78 which are provided with apertures 82, 99 for rotatably supporting shutters 84, but in the more expensive embodiments of the invention, the frame members 75, 78 are preferably provided with separate bearing strips 80 comprising elongated strips 16 of bearing metal or other non-corrodable material, such as brass or bronze, riveted to the frame members 75, 78 and provided with apertures registering with the apertures 82, 99. The separate bearing strips 80 increase 20 the bearing surface of the trunnions in the shutter frame, thereby decreasing the amount of wear and decreasing the possibility of rattling after a long period of use.

It should also be noted that the present 25 invention is not confined to the location of shutters in front of the radiator core 23, but in some embodiments of the invention, the core and shutter may be reversed with respect to the engine, so that the flanges 26, 27 project 30 rearwardly from the core to support shutters located inside the radiator hood.

It will thus be observed that I have invented 35 an improved radiator shutter construction in which the shutter unit is supported upon frame members carried by the outer wall of the radiator core, and the shutter supporting flanges preferably form integral extensions of the side wall of the core. The radiator core and shutter are capable of long periods of 40 rough usage, without the possibility of damage to the fragile parts of the radiator core, and without possibility of rattling. The outwardly extending flanges carried by the radiator core also enclose the space between the shutter frame and the core, and serve to direct all of the air passing through the shutter frame, through the honeycombed portions 45 of the core.

While I have illustrated a preferred embodiment of my invention, many modifications may be made without departing from the spirit of the invention, and I do not wish to be limited to the precise details of construction set forth, but desire to avail myself of all 50 changes within the scope of the appended claims.

Having thus described my invention, what I claim is new and desire to secure by Letters Patent of the United States, is:

55 1. In a radiator shutter device, the combination of a radiator core having an outer casing with a pair of projecting flanges forming an extension of the air passage through said core, with a radiator shutter, comprising a frame, said frame being carried by said projecting flanges and said flanges enclosing the space between said frame and core to direct air through said device, and a plurality of movable shutters carried by said frame.

60 2. In a radiator shutter device, the combi-

nation of a radiator core having an outer casing with a pair of projecting flanges forming an extension of the air passage through said core, with a radiator shutter, comprising a frame, said frame being carried by said projecting flanges and said flanges enclosing the space between said frame and core to direct air through said device, and a plurality of movable shutters carried by said frame, said frame having inwardly projecting flanges and said frame being located inside said projecting flanges on said core.

65 3. In a radiator shutter device, the combination of a radiator core having an outer casing with a pair of projecting flanges forming an extension of the air passage through said core, with a radiator shutter, comprising a frame, said frame being carried by said projecting flanges and said flanges enclosing the space between said frame and core to direct air through said device, and a plurality of movable shutters carried by said frame, and means for adjustably mounting said shutter frame with respect to said core.

70 4. In a radiator shutter device, the combination of a radiator core having an upper and a lower water box and an intermediate core structure, said core structure being enclosed by a radiator core band, a pair of integral portions of said radiator core band projecting laterally beyond said core structure at each side of said radiator core, and a radiator shutter having a substantially polygonal frame and a plurality of shutters, said frame being fixedly supported on said radiator core by being secured to said core band flanges, said core band flanges extending over the major portion of the depth of the radiator shutter frame to direct the air passing through said shutters through said core.

75 5. In a radiator shutter device, the combination of a radiator core having an upper and a lower water box and an intermediate core structure, said core structure being enclosed by a radiator core band, a pair of integral portions of said radiator core band projecting laterally beyond said core structure at each side of said radiator core, a radiator shutter having a substantially polygonal frame and a plurality of shutters, said frame being fixedly supported on said radiator core by being secured to said core band flanges, and a radiator shell carried by a spout on said upper water box and having a fenestration located in said shell with a resilient flange engaging said shutter frame.

80 In witness whereof, I hereunto subscribe my name this 2nd day of December, 1929.

EDGAR G. PETERSEN.
